Ara Park Lacey,
INVENTOR.

UNITED STATES PATENT OFFICE.

ASA PARK LACEY, OF MINNEAPOLIS, MINNESOTA.

IRONING-TABLE.

SPECIFICATION forming part of Letters Patent No. 339,193, dated April 6, 1886.

Application filed February 9, 1885. Serial No. 155,426. (No model.)

To all whom it may concern:

Be it known that I, ASA PARK LACEY, a citizen of the United States, residing in the city of Minneapolis, county of Hennepin, and State 5 of Minnesota, have invented an Improvement in Ironing-Boards, of which the following description, in connection with the accompanying drawings, is a specification.

Figure 1 is a side elevation view showing to the board in position for use. Fig. 2 is a front elevation view. Fig. 3 is a plan view of the ironing-board. Fig. 4 is a perspective view of one end of the board, showing relative positions of the parts when closed up. Figs. 5 and 6 are enlarged details showing the manner of attachment to the wall or wainscoting.

This invention relates to improvements in ironing-boards; and it consists, essentially—

First. In the grooved cleat a' , securely fastened on the broad end of the board A, to prevent its warping, and as a means of more securely fastening the board B, which is permanently attached to the board proper by means of the iron hinges $c c$, as partially shown in Figs. 25 5 and 6. The cleat $a' a'$ is further shown in Fig. 3.

Second. In the means of fastening to the

wall, which is accomplished by the use of the hinged board B, with the iron hooks $e e$, Fig. 4, driven or screwed into the board, which 30 are inserted into the screw-eyes $i i$, securely fastened in the wall, Figs. 5 and 6. Board B is then turned up and held in position by the button n , attached to the board A by the screw b . The board B, acting as a lever on the cushion $r r$, fastened by tacks or screws to the board B, presses the hooks firmly into the screw-eyes, as in Fig. 6, and supported by the brace u , secures the ironing-board firmly but not rigidly to the wall. 35

Having thus described my invention, what I claim as new, and desire to secure by Letters Patent, is—

The board A, in combination with the cleat a' , the hinged board B, the cushions $r r$, hooks $e e$, screw-eyes $i i$, button n , and brace u . 45

In testimony whereof I have hereunto set my hand in the presence of two subscribing witnesses.

ASA PARK LACEY.
